JOSHUA F. VOGEL, OF TOLEDO, OHIO, ASSIGNOR TO THE GENDRON WHEEL CO., OF TOLEDO, OHIO, A CORPORATION OF OHIO.

HOOD FOR TOY AUTOMOBILES.

Application filed April 20, 1921. Serial No. 462,887.

To all whom it may concern:

Be it known that I, JOSHUA F. VOGEL, a citizen of the United States of America, residing at Toledo, in the county of Lucas and 5 State of Ohio, have invented certain new and useful Improvements in Hoods for Toy Automobiles, of which the following is a specification, reference being had therein to the accompanying drawings.

10 The invention relates to hoods for toy automobiles and consists in the novel construction as hereinafter set forth.

In the drawings:

Figure 1 is a perspective view of the 15 automobile with the running gear omitted;

Figure 2 is a longitudinal section through the hood.

The frame of the automobile may be of any suitable construction, but as shown comprises the sill members A, on the rear portion of which is mounted the seat B and on the forward portion the hood C. This hood is formed of sheet metal fashioned to conform at its forward end to a head-board D 20 representing a radiator and at its rear end to a board E representing the instrument board of the car. The board D is secured to a cross bar F, which extends between the sills A. The front end of the hood is 25 smaller than the rear so as to give a tapering form and at the base and front the metal is bent outward at G in the plane of the upper face of the sills and is secured thereto by nailing as indicated at I. The 30 rear portion of the hood extends down outside of the sills and is secured by nailing as indicated at J.

In order to strengthen the hood, I have 35 formed the same with a central raised and substantially flat panel K, which extends from the forward to the rear end. At the rear end the hood is provided with a bead L and it is preferably also provided with 40 beads M near the forward end. Thus the 45 structure is greatly stiffened and strengthened, as well as producing a novel and pleasant

ing appearance. The flattened panel is further useful as forming a convenient place for marking with the manufacturer's name, trade-mark or other marking. 50

What I claim as my invention is:

1. The combination with a vehicle frame including a pair of sill members, of a cross-bar extending between said sill members and secured thereto, a head-board located 55 between said sill members and secured to said cross-bar, said head-board having a portion thereof fashioned to represent a radiator, a hood formed from a single piece of material having laterally extending portions secured to the upper faces of said sills and having depending portions secured to the side faces of said sills, a projection upon said head-board, said hood being secured to said head-board and having a longitudinally extending integral panel engaging 60 said projection, and an instrument board conforming in shape to said hood and secured thereto. 65

2. The combination with a vehicle frame 70 including a pair of sill members, of a cross-bar extending between said sill members and secured thereto, a head-board located between said sill members and secured to said cross-bar, said head-board having a portion 75 thereof fashioned to represent a radiator, a hood formed from a single piece of material having laterally extending portions secured to the upper faces of said sills and having depending portions secured to the side faces 80 of said sills, a projection upon said head-board, said hood being secured to said head-board and having a longitudinally extending integral panel engaging said projection, an instrument board conforming in shape 85 to said hood and secured thereto, a seat secured to said sill members and spaced from said hood, and means for reinforcing said hood.

In testimony whereof I affix my signature. 90

JOSHUA F. VOGEL.
